United States Patent Office.

RICHARD T. CRANE, OF CHICAGO, ILLINOIS.

Letters Patent No. 67,505, dated August 6, 1867.

STEAM-GENERATOR FOR HEATING PURPOSES.

The Schedule referred to in these Letters Patent and making part of the same.

TO ALL WHOM IT MAY CONCERN:

Be it known that I, RICHARD T. CRANE, of Chicago, in the county of Cook, and State of Illinois, have invented a new and useful Improvement in Steam-Generators; and I do hereby declare and make known that the following is a full, clear, and exact description thereof, reference being had to the accompanying drawings and the letters and figures marked thereon, which form part of this specification.

My invention relates to that class of steam-generators which are used for generating steam for heating purposes; and to enable those skilled in the art to understand how to make and use my said invention I will proceed to describe its construction and operation with particularity, making reference in so doing to the aforesaid drawings, in which—

Figure 1 represents a front elevation of my invention.

Figure 2 is a side elevation of the same.

Figure 3 is a rear view or elevation thereof.

Figure 4 is a plan section thereof, taken at the line *z* in fig. 2; and

Figure 5 is a detached view of the soot-scraper viewed from the rear.

Similar letters of reference in the several figures denote the same parts of my invention.

A represents the brick wall enclosing the generator, which is provided with the doors *D*, through which the fuel is introduced, and *D'*, from which the ashes are removed, as shown, fig. 2, and also the door at the rear end, marked *B* in said fig. 2, and one at the side, marked *C*, shown in fig. 1, said door *C* being a long, narrow one, at about midway from front to rear, extending nearly from top to bottom; said last-mentioned doors *B* and *C* being for the purpose of enabling a hose to be used to clean and wash the soot and ashes from the pipes as they may require it. The generator hereinafter described is composed of a series of pipes or coils, as shown, the entire fire-box being constructed of said water pipes, the water being introduced into said generator at *e*, as shown in fig. 2, being received into a header, *E*, from which the pipes *F*, forming the bottom and rear portions of the fire-box, open, being connected with the vertical headers *G* shown at the rear of the generator. From said header *E*, at each end thereof, pipes *H* lead into two vertical headers, *I I*, on each side of the fire-box, and of the same height as said fire-box, which are connected by a series of pipes passing around horizontally and forming the sides of the fire-box, and passing across the rear thereof, as seen in fig. 2. From the upper ends of said headers *I* pipes *K* extend up, and connect with the upper part of the generator at *N*, as shown in the drawings, to allow any steam which might form in the pipes *J* to pass up into that part of the generator which is occupied by steam. The pipes *F* open into a series of vertical headers, *G*, at the rear of the apparatus, as before mentioned, which extend to the top of the apparatus, from each of which headers a system of pipes extends over to the front of the apparatus, where they are returned again into said headers *G*, as shown, the lower series of said pipes *L* forming the top of the fire-box, the smoke and heat from the fire passing up through the interstices between the pipes to the top of the apparatus, whence the draught passes down the space *X* between the headers *G* and the rear wall, as seen in fig. 2, where it passes into the flue and escapes. It will be observed that the various pipes *L* do not return to the headers *G* in the same vertical plane in which they pass to the front, but are arranged diagonally, as clearly shown in figs. 1 and 3.

The object of this arrangement is to more thoroughly expose the whole system of pipes over the fire-box to the action of the heat passing up through them, which obviously is the practical result thereof. The pipes *L*, instead of returning, as shown, might terminate at the front of the apparatus, either separately or in suitable headers. The upper series of pipes, passing forward from the headers *G*, terminates in a series of heads, *M*, each of which receives four pipes, as represented, and from each of which a pipe, *N*, leads into a receiver, *O*, whence it is distributed as desired. The heads *M* form also a sort of receptacle, in which condensed steam will remain, and in the reservoir or receiver *O* a pipe, *P*, takes the condensation, and returns it to the lower part of the generator at *E*, as shown. The upper part of the apparatus is occupied by steam, the water occupying the entire lower part thereof, rising to any desired height, which water-mark or line may be determined by a stop-cock or a series thereof. A scraper, *Y*, shown in fig. 5, may be arranged upon the top of each horizontal series of pipes *L*, having a long rod or handle projecting from the front, to enable one to remove the soot and ashes accumu-

lating upon said pipes by drawing said scrapers backward and forward on the pipes; but the more effectual mode of cleaning them is by means of a hose showering them through the openings B and C, before mentioned, which are designed for that purpose. Between the pipes F, forming the bottom of the fire-box, are arranged a series of movable bars, R, resting at each end upon the rods T S, the one marked S, under the rear ends of said bars, being stationary, and the one at the front, T, having a rocking motion in suitable bearings, which motion may be imparted thereto by means of a handle thereupon, marked U. There is a notch, r, under the front ends of said bars R, in which a projection or rib, t, upon the shaft T, lies, as shown in fig. 2. The rear ends of the said bars are sloped, as indicated in fig. 2, so that when the said bars are moved longitudinally back by the rotation of the shaft T and the projection t, the rear end of said bars will be also raised up, the front ends being raised by the direct operation of the projection t while giving it the backward longitudinal movement aforesaid. Thus, by giving the shaft T a rocking motion, the said movable bars R are moved backward and upward, and forward and downward, so as thoroughly to shake down the ashes from the grate as desired. The effect of the said vibratory movement of the bars R will be enhanced by constructing said bars with notches, marked a in the drawings, upon their top, but they may be used without said notches if desired; and said bars may also be supported and operated in any suitable manner, so that they effect the desired result. Having described the construction and operation of my invention, I will proceed to specify what I claim, and desire to secure by Letters Patent.

1. I claim the arrangement of movable bars R in combination with stationary water grate-bars, substantially as and for the purposes specified.
2. I claim the combination and arrangement of the vertical headers G and the horizontal pipes L, substantially as specified and shown.
3. I claim the combination of the water grate-bars F with said headers G and pipes L, arranged and operating substantially as specified, and for the purposes described.
4. I claim the arrangement of the pipe or pipes K with the pipes J and headers I I, substantially as and for the purposes specified.
5. I claim the arrangement of the heads M, when constructed so as to form a water-drip for condensed steam, as set forth and described.
6. I claim the arrangement of the pipes N with the receiver O, so as to form a drip for the condensed steam in said receiver, and in combination with the pipe P, substantially as and for the purposes specified.
7. I claim the combination of the three systems of pipes F, J, and L, when connected and arranged in the manner herein set forth and shown, and for the uses specified.
8. I claim the arrangement of a series of scrapers, Y, in combination with a series of horizontal pipes, L, as and for the purposes specified and shown.

R. T. CRANE.
